UNITED STATES PATENT OFFICE

ARTHUR A. ALLEN, OF BELLEROSE, NEW YORK, ASSIGNOR TO THE PEELLE COMPANY, OF BROOKLYN, NEW YORK, A CORPORATION OF NEW YORK

ELEVATOR DOOR

Application filed April 5, 1930. Serial No. 441,872.

My invention relates to elevator doors, and more particularly to a construction of such doors wherein a light of glass is provided for permitting observation through a small portion of the door as a matter of convenience to the operator of the car.

Elevator doors of the type to which my invention relates are used extensively as fire retardants, and serve not only as closures for the openings of an elevator shaft, but to prevent flames, smoke and fumes, in the event of fire, from passing to or from the elevator shaft through the door openings on the various floors of a building.

15 If such doors, upon being subjected to severe tests, are found to materially reduce the fire hazard in the respects above noted, there may be a material reduction in the insurance rates upon buildings equipped with 20 such doors. In the United States, doors of a type which have been tested and approved by certain laboratories recognized by the insurance companies are inspected by the representatives of such laboratories during manufacture, and have labels showing such inspection and approval applied thereto, such doors becoming what is known as labelled doors, and the users thereof being entitled to all of 25 the advantages as to lowered insurance rates 30 growing out of the presence in a shaft of such doors.

Prior to my invention, the use of a vision or observation light of glass in any door immediately removed it from the class of labelled doors, notwithstanding that it has long been the practice to use wired glass lights inclosing such vision openings.

To obviate the above condition, I have produced an elevator door provided with a sight 40 or observation opening closed by a light of glass in the usual manner, which door is equipped with a non-inflammable closure plate of fairly heavy gauge sheet metal normally held in a position to expose the sight 45 opening by a member held in position by a fusible link. Said member and said link are positioned within the sight opening so as to be immediately made inoperative to maintain the closure plate or shutter in its elevated position before the temperature about the light

of glass closing the opening has become sufficiently high to cause any likelihood of the fracture of the glass and the consequent formation of an opening through the door.

The shutter, while mounted in guides positioned on one face of the door, is nevertheless so constructed that when it reaches the fully closed position, it will engage the door structure and thus come to rest completely closing the opening, and remain in this position. The 55 shutter closes entirely by gravity and its action is automatic.

By locating the restraining fusible link close to the light of glass, the shutter may be released as a result of the development of excessive heat upon either side of the glass.

The manner of mounting the light of glass is such as to minimize likelihood of accidental fracture of the glass during normal conditions of use of the door.

The invention consists primarily in an elevator door embodying therein a fire retardant panel having an opening therethrough, a light of glass secured within said opening and closing same, metal guides upon opposite sides of, and extending above, said opening upon one side of the door, a metal shutter slidably mounted in said guides, a member mounted within and adjacent one lateral side and the top of said opening and projecting part way across same, means carried by said shutter engaging said member, and a fusible link mounted within said opening and engaging said member, whereby with the fusing of said link the shutter will displace said member and descend by gravity; and in such other novel features of construction and combination of parts as are hereinafter set forth and described, and more particularly pointed out in the claims hereto appended.

Referring to the drawing,

Fig. 1 is a condensed view in elevation of an elevator door embodying the invention;

Fig. 2 is a fragmentary section thereof upon an enlarged scale on the line 2-2 of Fig. 1; and

Fig. 3 is a horizontal section also upon an enlarged scale upon the line 3-3 of Fig. 1.

Like numerals refer to like parts throughout the several views.

In the embodiment of the invention shown in the drawing, 10 indicates an ordinary wood core, metal sheathed door section, the detailed construction of this section being omitted except in so far as is necessary to the understanding of the present invention.

Extending through this door panel is an opening shown at 11, the edges of this opening being protected by the sheathing of the door, as shown at 12. Within the opening is positioned a light of glass 13 which may be of any desired type, heavy wired glass ordinarily being used. This light of glass 13 substantially closes the opening 11, it being of sufficiently smaller diameter than said opening to permit expansion thereof and minimize likelihood of the breaking of the glass either as a result of such expansion or as a result of severe jolts to which said doors are subjected.

The light of glass is frictionally held in position by means of cast metal rectangular plates 14 and 15 having flanges 16 directed inwardly of the opening and of the sides of the door into engaging relation with the glass 13 along a line spaced from the walls of the opening. One of these plates 14 is provided with flanges lapping the door about the edge of the opening, being drawn tightly against the door by means of screw bolts or other devices so as to develop the desired frictional engagement with the glass 13. The other plate 15 is provided with a flange abutting the walls of the opening and secured thereto by means of screws, or in any other desired manner, this plate also having flanges 17, similar to the flanges 16, and like said flanges 16 frictionally engaging the light of glass. These plates and flanges extend entirely about the opening.

The top bar of one of the plates as 15 has formed thereon depending lugs 18 and 19 adjacent the opposite sides of the opening respectively. One of these lugs as 18 supports a pivotal member or link 20, which is adapted to have a free turning movement about a pivot 21. The other lug 19 has secured thereto, in any desired manner, a fusible link 22, the other end of which is secured by means of a screw 23 or other mechanical device to the free end of the pivotal member or link 20.

The fusible link 22, under normal conditions, affords a rigid support for the free end of the member or link 20, thus presenting a normally rigid bridge or barrier across and closely adjacent the opening 11. Both the pivotal and the fusible links are located, in their entirety, within the opening 11 fairly closely adjacent the light of glass, so that excessive heat upon either side of this light of glass will fuse the material of the link 22 before a sufficiently high temperature has developed to fracture or fuse the light of glass. Ordinarily, these fusible links are made of a metal composition, fusible at a

temperature but slightly above the maximum temperature to which they may be subjected under normal conditions.

Secured to one face of the door or door section 10, upon opposite sides of the opening 11, are vertically extending guides or tracks 24 and 25. Preferably, these guides or tracks 24 and 25 are formed of a single strip of sheet metal, bent upon itself and provided with an offset, shown at 26, to provide the necessary clearance for the free movement of a shutter 27 mounted in said guides. These guides preferably extend beyond the side edges of the opening 11, not only for the purpose of affording adequate guiding areas for the shutter, but for effectively closing the sides of the opening adjacent the plate 15. They are of a length to guide and support the shutter when passing from the fully open to the fully closed positions, and when in such positions.

The shutter 27, at the bottom thereof, is provided with an inturned flange 28 extending within the opening 11 into engageable relation with the pivotal link 20, this flange, however, being narrower than the shutter so as to pass freely between the bearing lugs 18 and 19 and avoid possibility of the engagement of said flange with said lugs in a manner to interfere with the free vertical sliding movement of the shutter in the event of the fusing of the link 22.

The channels in the guides 24 and 25 are of a width and depth sufficient not only to permit a free sliding movement of the shutter 27, but to permit the expansion of this shutter without likelihood, in the event of fire, of its being warped in a manner to interfere with such free sliding movement.

The top edge of the shutter 27 is provided with an inturned handhold flange 29 for use in mounting the door in the guides 24 and 25, or when restoring the fusible link connection after the shutter has been automatically actuated.

The operation of the structure above referred to is substantially as follows:

When constructing the door or door section, the malleable cast metal plate 15 is secured adjacent one edge of the opening 11. The light of glass 13 is then positioned within the opening against the flange 17, and the casting 14 temporarily connected with the face of the door or door section upon the opposite side of the opening. The guides 24 and 25 are then brought into position upon the face of the door opposite that to which the plate 14 is attached, and secured in position by means of bolts passing through the door and engaging the side flanges of the casting 14.

Before tightening the securing means for the plate or casting 14, the light of glass 13 is set in relation to the opening so as to bring all edges thereof away from the wall

of the opening. When the light of glass is so positioned, the securing means for the plate or casting 14 are tightened down, thus developing sufficient friction between the light of glass and the flanges 16 and 17 of the plates or castings 14 and 15 to hold the light of glass in its position with clearance about all edges thereof.

5 The pivotal member or link 20 is then mounted upon the pivot 21 carried by the lug 18 and the fusible link 22, rigidly connected with the free end of the link 20 and with the lug 19, thus forming a barrier across the opening 11 closely adjacent the top thereof.

10 15 This barrier is located in its entirety within the opening and spaced away from the plane of the channel of the guides 24 and 25.

20 The shutter 27 is then mounted in the guides 24 and 25 by merely allowing it to drop downwardly through the open top of the channels of said guides until the flange 28 engages the link 20, which arrests further movement of the shutter, thus maintaining it in the open position. The handhold flange 25 29 may be used to check a too rapid descent of the shutter.

25 When the parts are in this position, the light of glass 13 is exposed throughout substantially its entire area so as to permit a free 30 observation therethrough. There is no likelihood, under normal conditions, of the accidental falling of the shutter 27 so as to obscure the opening 11. This is the normal condition of a door embodying the invention.

35 In the event of fire, however, a very slight elevation of temperature, possibly 20 to 25° will result in the fusing of the material of the link 22, thus depriving the free end of the pivotal link 20 of its support. The weight 40 of the shutter will aid in the rapid breaking down of the fusible link.

45 Immediately that the fusible link gives way, the pivotal link 20 drops, thus removing the support for the shutter and permitting it to descend by gravity until the flange 28 engages the bottom wall of the opening 11, thus effectively closing said opening and preventing the passage of fire, smoke or fumes therethrough.

50 When it is desired to again expose the opening, the handhold flange 29 is used to raise the shutter, the pivotal link 20 is restored to its engaging position with the flange 28 and a new fusible link 22 is connected with the lug 19 and with the free end of the pivotal link 20.

55 The link 20 extends only part way across the opening 11, and the fusible link 22 is positioned well within this opening, this link 60 being of as great a length as is practicable considering the low compressive strength of the material of the link and notwithstanding its channelled formation as shown in the drawing. This locating of the link well 65 within the opening is necessary in order to

expose it to the heat well away from the side walls of the opening which might tend to protect the fusible link from the effects of such heat until excessively high temperatures have developed. The point of connection of the fusible link 22 with the pivotal link 20 permits the effective application of the weight of this link and of the shutter to ensure a quick breaking down of the link when it has been weakened by heat, and a prompt closing of the shutter.

70 It is not my intention to limit the invention to the precise details of construction shown in the accompanying drawing. Instead of using cast metal plates 14 and 15, sheet metal plates may be used in lieu thereof if desired, but the cast metal plates have been found more desirable in actual practice. Furthermore, the formation of the guides 80 85 24 and 25 as shown is not essential, although this method has also been found highly satisfactory in use.

Having described the invention, what I claim as new and desire to have protected by Letters Patent, is:—

90 95 1. An elevator door embodying therein a fire retardant panel having an opening therethrough, a light of glass secured within said opening and closing same, metal guides upon opposite sides of, and extending above, said opening upon one side of the door, a metal shutter slidably mounted in said guides, a member mounted within and adjacent one lateral side and the top of said opening and projecting part way across same, means carried by said shutter engaging said member, and a fusible link mounted within said opening and engaging said member, whereby with the fusing of said link the shutter will displace said member and descend by gravity.

100 105 2. An elevator door embodying therein a fire retardant panel having an opening therethrough, a light of glass secured within said opening and closing same, metal guides upon opposite sides of, and extending above, said opening upon one side of the door, a metal shutter slidably mounted in said guides, a link pivotally mounted within and adjacent one lateral side and the top of said opening and projecting part way across same, means carried by said shutter and engaging said link, and a fusible link mounted within said opening adjacent the side thereof opposite the point of pivotal support of said first named link extending part way across said opening and engaging said first named link, whereby with the fusing of said link the shutter will displace said pivotal link and descend by gravity.

110 115 120 125 3. An elevator door embodying therein a fire retardant panel having an opening therethrough, rectangular plates having inwardly directed flanges secured about said opening, a light of glass frictionally engaged by said inwardly directed flanges, metal guides upon

opposite sides of, and extending above, said opening upon one side of the door a metal shutter slidably mounted in said guides, a member mounted within and adjacent one lateral side and the top of said opening and projecting part way across same, means carried by said shutter engaging said member, and a fusible link mounted within said opening and engaging said member, whereby with the fusing of said link the shutter will displace said member and descend by gravity.

4. An elevator door embodying therein a fire retardant panel having an opening therethrough, rectangular plates having inwardly directed flanges secured about said opening, a light of glass frictionally engaged by said inwardly directed flanges, metal guides upon opposite sides of, and extending above, said opening upon one side of the door, a metal shutter slidably mounted in said guides, lugs carried by the top of one of said frames adjacent each lateral side of said opening, a link pivotally connected to one of said lugs and extending part way across the opening toward the other lug, and a fusible link connected with said other lug and the end of said first named link projecting well within said opening and engaging said pivotally mounted link, whereby with the fusing of said link the shutter will displace said pivotal link and descend by gravity.

5. An elevator door embodying therein a fire retardant panel having an opening therethrough, a light of glass secured within said opening and closing same, metal guides upon opposite sides of, and extending above, said opening upon one side of the door, a sheet metal shutter having a laterally reduced portion thereof bent to project within the opening, a link pivotally mounted within and adjacent one lateral side and the top of said opening and projecting part way across same in engageable relation with said inturned edge of said shutter, and a fusible link mounted within said opening adjacent the side thereof opposite the point of pivotal support of said first named link extending part way across said opening and engaging said pivotally mounted link, whereby with the fusing of said link the shutter will displace said member and descend by gravity.

6. An elevator door embodying therein a fire retardant panel having an opening therethrough, rectangular plates having inwardly directed flanges secured about said opening, a light of glass frictionally engaged by said inwardly directed flanges, metal guides upon opposite sides of, and extending above, said opening upon one side of the door, a sheet metal shutter having a laterally reduced portion thereof bent to project within the opening, lugs carried by the top of one of said frames adjacent each lateral side of said opening, a link pivotally connected to one of said lugs and extending part way across the

opening toward the other lug, and a fusible link mounted within said opening adjacent the side thereof opposite the point of pivotal support of said first named link extending part way across said opening and engaging said pivotally mounted link, whereby with the fusing of said link the shutter will displace said pivotal link and descend by gravity.

7. An elevator door embodying therein a fire retardant panel having an opening therethrough, rectangular plates having inwardly directed flanges secured about said opening, a light of glass frictionally engaged by said inwardly directed flanges, guides upon opposite sides of, and extending above, said opening upon one side of the door, each of said guides being formed of a single strip of sheet metal bent upon itself and provided with an offset to form a channel extending beyond the side edges of the opening, a flat sheet metal plate constituting a shutter slidably mounted in the channels of said guides, and having the lower edge thereof laterally reduced and bent inwardly of the opening, and having at the top thereof a laterally reduced portion bent away from the opening to form a handhold, lugs carried by the top of one of said frames adjacent each lateral side of said opening, a link pivotally connected to one of said lugs and extending part way across the opening toward the other lug, and a fusible link mounted within said opening adjacent the side thereof opposite the point of pivotal support of said first named link extending part way across said opening and engaging said pivotally mounted link, whereby with the fusing of said link the shutter will displace said pivotal link and descend by gravity.

In witness whereof I have hereunto affixed my signature, this 1st day of April, 1930.

ARTHUR A. ALLEN.
